ROLL BOX DOOR CONSTRUCTION FOR GINS

Frank E. Deems, Birmingham, Ala., assignor to
 Continental Gin Company, a corporation of
 Delaware

Application March 6, 1939, Serial No. 259,973

12 Claims. (Cl. 19—55)

My invention relates to improvements in the design, mounting, and manner of manipulation, of a door which is movable to give access to the roll box of a gin.

In the normal operation of gins, and particularly huller gins which have inner and outer breast members that are relatively movable to make provision for the dumping of the roll of cotton, seed and trash that collects in the roll box, it becomes necessary, from time to time, to have access to the roll box not only to facilitate the discharge of the roll when it does not fall out readily in response to the roll dumping manipulation of the outer breast, but also to inspect and clean or repair the ginning ribs forming part of the grate fall so as to maintain the efficiency of the gin.

It is also desirable that the door when opened to give access to the ribs for cleaning, should be adapted to prevent the falling into the hulling chamber of material from the roll as seed and lint cotton may thereby pass to waste with the hulls and trash.

It is also important that the door should be light and capable of ready and easy manipulation to assume opened or closed position.

One distinctive feature of my invention is that the door is adapted to assume any one of three positions, one being its normal or upright closed position and the other two being selective according to the open position desired, in one of which open positions the door does not obstruct communication between the roll box and hulling chamber of the gin, while in the other it effectively intercepts such communication.

More particularly, my present invention contemplates forming the door as a relatively narrow transverse arcuate member so mounted, as by means of end pins working in guides or otherwise, that in closed position its lower edge coacts with the front wall of the roll box and in its open positions its upper edge is brought into juxtaposition to, or cooperative engagement with, said front roll box wall.

A further distinctive feature of my door is that it is so mounted as to be capable of being inverted when being moved from closed to open position and so disposed in this latter position as to intercept the falling of material from the roll box into the hulling chamber.

It is a further distinctive feature of my invention that when the door is inverted and swung out to intercept communication between the roll box and hulling chamber, it is so mounted and disposed that it may be swung over rearwardly,

without opening its bottom joint with the roll box, thus enabling the operator with a quick movement of the door to flip back into the roll box all material resting on the door, preliminary to resetting the latter in closed position.

My invention further comprises the novel details of construction and arrangements of parts which, in their preferred embodiment only, are illustrated in the accompanying drawings, in which:—

Fig. 1 is a vertical transverse cross sectional view, taken through the double breast of a huller gin, with the outer breast swung open to roll dumping position and the roll box door shown in its closed operating position.

Fig. 2 is a similar view, broken away, with the front breast shown in closed position, and the door shown in full lines in one of its open positions and in dotted lines in the other of its open positions.

Fig. 3 is a partial front elevation of the inner breast and door as shown in Fig. 2, all of the front breast being omitted except the roll box elements carried by the front breast.

Fig. 4 is a detail sectional view through the door taken on the line IV—IV of Fig. 3; and

Fig. 5 is an exploded view illustrating in detail a screw guide pin and the manner of inserting it through the breast head and mounting it in the door.

Fig. 6 is a fragmental view looking at the outside of the inner breast head and illustrating the reinforcement thereof to make provision for the guide slots in which the end pins on the door work.

Similar reference numerals refer to similar parts throughout the drawings.

I have illustrated my invention as applied to a double breast huller gin comprising an inner breast 10 adjustably mounted by means of the grooved trunnion wheels 11 (Fig. 3) on track members 12 which are attached to the gin frame 13 at each end. I pivotally mount on the inner breast 10, by means of end pins 14 engaged in slots 15 in the forward end of said inner breast, an outer breast 16 which at its lower end is equipped with suitable mechanism, not shown, to releasably latch it below to the bottom portion of the inner breast so as to hold the breasts in assembled relationship while they are at work or being shifted on their trunnion supports.

I mount on the gin frame at each end a lug or shoulder 17 and connect to it pivotally a link 18 which in turn is pivotally connected to a crank 19. These cranks 19 are fast on a cross shaft 20,

- and at least one of the cranks has an arm 21 by means of which both cranks can be rocked together through the instrumentality of the shaft, causing the breasts to shift on their track supports 12 and to assume inner or outer position with relation to the gin, it being noted that as the breasts shift out the bottom end 22 of the inner breast will slide down along its inclined supports 23 that are secured to the base of the gin frame.
- 10 As a result of the foregoing arrangements, the double breast, as it moves outwardly on its tracks, will tilt forwardly and downwardly somewhat to increase the unbalanced condition of the outer breast so that the latter will, when unlatched, 15 swing open fully as shown in Fig. 1, to dump the roll.

While I have described somewhat in detail the construction and manipulation of the double breasts, it is to be understood that the same 20 forms the subject matter of companion application Serial No. 248,231 and Letters Patent No. 2,155,181 issued to me on 18th day of April, 1939, and are not specifically claimed herein, since my present invention is chiefly concerned with the 25 design and manipulation of the roll box door, which will now be described.

As is customary in huller gins, the seed cotton carrying more or less hulls and trash, falls first into the hulling chamber 25 in the outer breast 30 and passes down into engagement with the huller ribs 26 between which the toothed peripheries of the saws 27 pass when the breasts are in their normal operating position. These ribs 26 are suitably mounted upon lower and upper rib rails 35, 28 and 29, the latter having its inner face concave to receive the lower concave wall member 30 of the roll box 31, that is defined between said wall 30 below and the concave door 32 on the front and by the rear curved wall member 33 overhead and the ginning ribs 34 of the grate fall below, said ribs and member 33 being secured to the cross member 35 at the rear of the inner breast. The saws will therefore project through the ribs 34 as well as the ribs 26 when the 40 breasts are in working position, and the elements 45 30 and 34 will define a rounded chamber which is generally referred to as the roll box, because the saws act to draw cotton locks and some hulls and trash through the ribs 26 and force same upwardly over the ribs 34, causing same to rapidly accumulate and rotate in the roll box until a roll is formed which is driven by the action of the saws and from which roll the lint is continually being withdrawn through the grate fall 34 by the 50 teeth of the saws, and doffed in a manner well understood in this art.

In this roll more or less hulls, sticks and trash accumulate and from time to time it is necessary to dump the roll. At other times it is necessary 55 to open up the roll box to get access to the saws for inspection, or to the grate fall for the cleaning and removal of obstructions or chokes that may be reducing the efficiency of the unit.

These operations require access to the roll box for which reason it is necessary that the door 32 be movable so as to afford such access. The door, as shown, comprises the inner arcuate plate 32a, joined at its upper edge by a curved top 36 to a front plate 37 which extends down first in spaced 60 relation to the face 32a and then into engagement with said plate to which it is welded or otherwise made fast. In the bight 36, at each end of the door, I weld or otherwise make fast a cylindrical element 38 having an axial hole tapped therein 65 for the reception of a screw pin 39 (Fig. 5) adapt-

ed to be inserted freely through a hole 40 in a boss 41 on each head of the inner breast 10. One pin 39 is screwed into the bore of each element 38 so as the to leave its plain outer end 43 in position to clear the inner end of the hole 40 of its respective boss but to be engaged in a slot or groove 42 arranged to guide the movements of the door.

It will be observed, by reference to Figs. 1 and 2, that the holes 40 are located at the upper end 10 of the grooves 42 which extend forwardly and downwardly, preferably in a curve substantially conforming to the curvature of the roll box. At its lower end each groove is enlarged as will more clearly appear in Fig. 6, where the boss 41 is shown extended downwardly following the path of the groove and serving to reinforce the breast head where reduced to form the groove.

The pin heads 43 projecting from the ends of the door constitute guides to control the movement of the upper end of the door to assume its several positions, these pins being free to move in the groove 42 until they reach the bottom of the slots and there to have room for a slight outward displacement for the purposes later described.

To or along the bottom edge of the door I suitably attach a stop means such as an angle strip 44 which projects below the adjacent door edge and is offset therefrom sufficiently to receive the upper edge of the roll box front wall member 30 carried by the outer breast 16. This member 30, in its preferred construction, is bent back outwardly and downwardly upon itself to form a front brace member 45, which at its lower edge 35 overlaps and is attached to the front face of the top rib rail 29, and to end angle irons 46 which are secured to the outer breast heads. The upper edge of the member 30 is preferably disposed substantially above the level of the roll box axis, thereby enabling me to narrow the vertical width dimension of the door and reduce the tendency of material to fall from the roll into the hulling chamber 25 when the door 32 is open. The angle irons 46 have inclined top edges sloping downwardly from the upper level of the rib rail 29. I provide on the forward upper corner of each head of the inner breast, near the pivot point 14, an inner lug or shoulder 47. I cut notches 48 (see Fig. 3) through the front door members 37 and close the side and upper walls of each notch by inserting a U-shaped plate 49 and securing it in position between the inner and outer faces of the door, thus forming hand grips for the manipulation of the door in the manner which will now be described.

Assuming the door in closed position, its lower edge rests on and is held in engagement with, the upper edge of the member 30, and its upper edge is held in place by the engagement of the pins 39 in the upper end of the grooves 42.

As shown in Fig. 1, the door has shifted downwardly enough to follow the movement of its supporting member 30 on outer breast 16 as the latter is swung out to roll dumping position. When the outer breast is thrust back to normal working position and latched there, its member 30 will move rearwardly and upwardly pushing the door upwardly ahead of it until its guide pins 39 approach, but do not entirely reach, the top end of the grooves 42. This constitutes the normal closed operating position of the door, and when so disposed there still remains sufficient room between the pins 39 and the extreme upper end of the grooves 42, to permit the door to be

pushed up just far enough for the lower edge of its front plate designated 32a, but not its stop member 44, to clear the member 30, whereupon the door is free to be swung forwardly on its pins 39 as pivots, to clear 30 and then moved to assume either of its open positions shown in Fig. 2.

If it be desired simply to drop the door into position to give access to the roll box, regardless of whether material in the roll box will fall over into the hulling chamber 25, then after its lower edge is clear of the member 45 it will drop down until its pins 39 reach the lower end of the grooves 42, and its rounded edge engages member 30, causing the pins to shift forwardly in the enlarged lower ends of the grooves and the door to hang down freely in the hulling chamber with its lower edge engaging the stops 46. To open the door from this position, it is thrust upwardly until its pins 39 strike the top of the grooves 42, when by gravity the bottom edge of plate 32a can swing rearwardly over member 30 but its stop member 44 will strike member 45, whereupon the door when released will drop and the pocket along its lower edge will telescope over and interlock itself with the members 30, 45, as shown in Fig. 1.

If it be desired so to manipulate the door that in its open position it will prevent material escaping from the roll box into the hulling chamber, then the door is grasped by its hand holds and lifted to free the bottom edge of 32a from the member 30, and shift the pins 39 to the upper end of the grooves 42 which places the door in position for its lower edge as it is swung upwardly to clear the shoulders 47 on the inner breast heads. When this occurs the upper end 38 of the door can be swung downwardly until the pins 39 reach the bottom of the grooves 42 and then the door, when released, will fall outwardly and rest in inverted position against the shoulders 47 and the roll box wall members 30, 45, which is the full line position of Fig. 2. The door will now form a forwardly and upwardly inclined shelf upon which material, as the operator opens up the roll, is free to fall and which will prevent this material escaping into the hulling chamber 25. After the ribs have been cleaned to remove a choke or repaired and it is desired to return any material resting on or against the door back into the roll box, the door is swung on its pins 39 as pivots and with its rounded edge 38 remaining in contact with the member 30 so that its free edge follows the path of the dotted line in Fig. 2, which will dump any material resting on or against it into the roll box, after which the door is raised, drawing its pins 39 back to the top of the grooves 42 when it can be swung rearwardly and downwardly until its stop 44 engages the member 45 and then, upon release of the door, it will drop automatically into locked working position with wall 30. It is, of course, necessary to fully open the forward upper portion of the roll box above its wall member 30 in order to shift the door to the full line open position of Fig. 2, but as a general rule no objectionable amount of material will fall over into the hulling chamber 25, because the roll itself will not be disturbed particularly by the manipulation of the door, and the fixed wall member 30 of the roll box rises enough above the level of the roll box center to hold the roll material therein. The enlargement of the grooves 42 at the bottom allows the pins 39 to shift out enough to give freedom for play of the edge 38 of the open door, as it is manipulated, to assume its

various positions and to perform the functions hereinabove described, and yet gravity will tend to hold the edge 38 against the top edge of member 30 in all open positions of the door.

While I have shown my invention in but one form, it will be obvious to those skilled in the art that it is not so limited, but is susceptible of various changes and modifications, without departing from the spirit thereof, and I desire, therefore, that only such limitations shall be placed thereupon as are imposed by the prior art or as are specifically set forth in the appended claims.

What I claim is:

1. In a gin having elements defining a roll box and comprising a lower front wall element and a movable upper front wall element forming a door, and guide means for the door constructed and arranged to permit either the upper or lower edge of the door to be presented to said lower front wall element.

2. In a gin having elements defining a roll box and comprising a lower front wall element and a movable upper front wall element forming a door, guide pins near the upper edge of the door at each end, and downwardly and forwardly inclined guides on the gin in which said pins are free to move so as to permit either the upper or lower edge of the door to be presented to said lower front wall element.

3. A gin according to claim 2, in combination with stop elements disposed to permit the free edge of the door to swing upwardly past them on said pins as pivots when the latter stand at the upper end of their guides, said stops being adapted to support the free edge of the door when its guide pins stand at the lower end of their guides.

4. A gin according to claim 2, in which the gin is free of elements that would prevent the door being opened by being dropped bodily downwardly so as to hang from its guide pins in front of the lower front wall member of the roll box.

5. In a huller gin, elements defining a hulling chamber and a roll box, the front wall of the roll box comprising a lower member stationary with respect to its supports and an upper door member movable with respect to its supports, means to hold the lower edge of the door member in working relation to said stationary member, movable door mounting means constructed and arranged to permit said members to be disengaged, the gin being free of obstruction to permit the lower edge of said door member when free to be swung upwardly and forwardly and its top edge downwardly to present the door in inverted upwardly and forwardly inclined position with its top edge juxtaposed to said lower stationary member, and stops to hold said door member in said latter position while access is being had to the roll box.

6. A gin according to claim 2, in which the hulling chamber is free of any elements in the path of said door member when in inverted position that would prevent its free edge being swung upwardly and rearwardly into position to dump any material resting thereon back into the roll box.

7. A gin having members defining a hulling chamber and a roll box, the front concave wall of the roll box comprising an upper movable door and a lower fixed wall to the upper edge of which the lower edge of the door is normally juxtaposed, and guide pins adjacent to the upper edge of said door, downwardly and forwardly disposed guides

for said pins, and a stop clip on the bottom edge of the door forming a pocket adapted to straddle the upper edge of said fixed wall and detachably hold the door in normal position, said pins and slots permitting the door to be displaced relatively to said fixed wall to give access to the roll box.

8. A gin having members defining a hulling chamber and a roll box, the front concave wall of the roll box comprising an upper movable door and a lower fixed wall to the upper edge of which the lower edge of the door is normally juxtaposed, and guide pins adjacent to the upper edge of said door, downwardly and forwardly disposed guides for said pins, a stop lip along the bottom edge of the door forming therewith a pocket adapted to straddle the upper edge of said fixed wall to detachably hold the door in normal position, said pins and slots permitting the door to be displaced relatively to said fixed wall to give access to the roll box, and stops for said door disposed to clear the lower edge of the door when it is swung upwardly about said guide pins when they are in position at the upper ends of their respective guides, and adapted to form supports for said lower edge of the door when its upper edge is moved downwardly in its guides into juxtaposition to said fixed wall.

9. In a gin, elements defining a roll box, the front concave wall of said box comprising a lower fixedly mounted wall and an upper door movably mounted to give free access to the roll box from above, said door comprising guide pins projecting from the top of its end edges, and guides on the end walls of the gin to coat with said pins, there being openings formed through said guides to permit the mounting of the inner ends of said pins in the ends of said door, and said door being movable about and guided by said pins to assume its open or closed working positions.

10. In a gin, having relatively stationary elements forming the major portion of a roll box, a moveable door element forming the upper forward wall of the roll box and comprising an arcuate metal plate with stop and latch means on its lower edge to engage and interlock it with a roll box wall, the upper edge of said door being bent over and outwardly to define a rounded top edge, handles provided on said door, blocks secured in the ends of the bight at the top of the door, guides in the end walls of the roll box in which said pins work, and apertures in said guides to permit said pins to be inserted in said blocks through the end walls to mount the door in position, said guides being disposed to permit the door when inverted to present its upper edge into juxtaposition to the upper edge of the stationary front wall of the roll box on which its lower edge had been mounted.

11. A gin according to claim 2, in which the lower edge of the door in its normal operating position is provided with stop means which underhangs its lower edge and is spaced therefrom so as to straddle the upper edge of the lower front wall element when the door is in normal closed position, said stop means being so disposed as to engage said wall element when said guide pins are at the extreme upper ends of their guides, thereby to prevent the free edge of the door swinging inwardly into the roll box while said guide pins are engaged in said guides.

12. In a huller gin having a roll box and hulling chamber, a door forming part of the upper front of the roll box, mounting means for said door which permit it to be inverted to give access to the roll box, and means to support the inverted door in position to intercept escape of material from the roll box into the hulling chamber.

FRANK E. DEEMS.
